Specification for Design.

Patented Mar. 19, 1918.

Application filed January 9, 1917. Serial No. 141,490. Term of patent 14 years.

To all whom it may concern:

Be it known that I, FLORENCE L. GRANT, a citizen of the United States, residing at Monaca, county of Beaver, State of Pennsylvania, have invented a new, original, and ornamental Design for Shades, Reflectors, or Similar Articles, of which the following is a specification, reference being had to the accompanying drawings, forming part thereof.

Figure 1 is a front view of the shade or reflector embodying my invention; Fig. 2 is

a side view thereof; and Fig. 3 is a top plan view.

I claim:

The ornamental design for a shade, reflector, or similar article substantially as shown.

In witness whereof, I have hereunto set my hand this 27th day of December, 1916.

FLORENCE L. GRANT.

Witness:

PAULUS E. KOEHLER.
